UNITED STATES PATENT OFFICE.

JAMES H. HILL, OF BELLEVILLE, CANADA.

LANTERN.

SPECIFICATION forming part of Letters Patent No. 628,804, dated July 11, 1899.

Application filed January 17, 1898. Serial No. 666,992. (No model.)

To all whom it may concern:

Be it known that I, JAMES H. HILL, of the city of Belleville, in the county of Hastings, in the Province of Ontario, Canada, have invented certain new and useful Improvements in Lanterns; and I do hereby declare that the following is a full and clear description of the same.

My invention relates to lanterns, and has for its object to provide improved means for hinging the air-tubes and parts carried by the same to the oil-cup; also, improved means of sustaining the globe-plate; also, an improved construction and arrangement of globe-holder and air-chambers connected therewith, and also to generally improve various features of the lantern.

The invention consists in the construction and also the combination of parts, as will be hereinafter described and then sought to be specifically defined by the claims, reference being had to the accompanying drawings, forming a part hereof, and in which—

Figure 1 is a side view of the lantern with the globe portion thrown backward. Fig. 2 is an elevation looking from the rear of the lantern, and Fig. 3 is a sectional outline view of the upper portion of the lantern.

In the drawings the letter A designates the oil-cup, which is provided with a burner-collar B, permanently secured to the top of the oil-cup. To this collar and resting upon the top of the oil-cup is permanently secured, by rivets or otherwise, two ears C, connected together at their base by a cross-plate D and which constitute the lower member of the hinge by which the air-tubes E and parts carried thereby will be hinged to the oil-cup. The second member of this hinge consists of the ears C', connected together by a plate D' and hinged by pivots to the ears C of the other member of the hinge. The lower ends of the air-tubes E communicate with the interior of the burner-collar B through openings made in the ears C' and also through openings made in the ears C, the openings in the two members of the ears registering when the air-tubes are in upright position, so as to permit the air to pass down the tubes and into the burner-collar. By forming the hinge of the two ears as constructed and connected together as described a very strong and sub-

stantial hinge is provided, so that the life of that member is increased to quite an extent. The globe-plate F, which in practice will be perforated, as usual, is supported from the air-tubes E by the wires G, which will be connected permanently at one end to the tubes and at the point next to the globe-plate will be curved so as to conform to the globe-plate and will be soldered to that plate. This plate will also rest upon the cross-plate D' of the ears C' and be permanently secured thereto by rivets or solder or otherwise. This construction imparts firmness and rigidity to the globe-plate.

The air-tubes E at their upper ends support a collar H, which will have an outwardly-extending flange I at its lower end and an inwardly-projecting flange J at its upper end. Inside of this collar is placed the sliding sleeve or collar K, the lower end of which is adapted to encircle the upper end of the globe L, so as to hold the same in place upon the globe-plate F, the lower end of the sliding sleeve or collar K being formed with perforations, as shown. This sliding sleeve or collar is supported within the collar H by means of a spiral spring M, which at one end will bear against the inwardly-extending flange J of the collar H and at the other end bear against any suitable projection or shoulder on the sliding sleeve, so that by lifting the sleeve the spring will be contracted and when released the pressure of the spring will recoil and carry the sliding sleeve to its position against the upper end of the globe L. The sliding sleeve K in connection with the fixed sleeve or collar H forms an air-chamber N, with which the upper ends of the air-tubes E communicate. This sliding sleeve is also formed with openings O, communicating with the chamber N, and the outside collar H is provided within its lower flange I with openings P.

Inside of the upper portion of the sliding sleeve or collar K is secured a conical or tapering collar or tube Q, which forms converging walls in the interior of the upper portion of the sliding sleeve K, and also a chamber R between such conical sleeve and the outer wall of the sliding sleeve K, which chamber will communicate with the chamber N through the openings O. A deflecting-plate S is supported slightly above the conical sleeve Q by

means of metallic strips T, and above this deflecting-plate the sliding sleeve K supports a hood or cover U, which may be provided with a lifting loop or ring V, openings W being formed in the upper portion of the sliding sleeve K just beneath the hood or cover U.

The globe-plate F is provided with a spring-catch X, which will engage a pin projecting from the burner-collar B, so as to hold the 10 air-tubes and parts carried thereby in an upright position.

The products of combustion pass up through the globe and the sliding sleeve at the upper end thereof and through the openings W at 15 the upper end of the lantern, the conical formation of the sleeve Q inside of the sliding sleeve tending to increase the upward draft. The air for supporting the combustion is received through the openings W and passes 20 down through the chamber R into the chamber N and thence down the air-tubes to the burner. Any rush of air which may pass in at the openings W is caught in the chamber K and will pass out through the openings P 25 in the collar H without passing down the globe, and hence protection is afforded against the flame being blown out by a strong current of air entering at the top and passing down through the globe to the burner.

30 When it is desired to remove the globe, it is simply necessary to lift the globe-holder or sliding sleeve K, so as to release it from engagement with the globe, when the globe may be lifted from position. In placing the same 35 in position the sleeve is raised and then the spring retracts the sleeve, so as to have it fit over the upper end of the globe.

The flange I to the collar H may be formed with perforations Z directly under the chamber N, as indicated in Fig. 3 of the drawings, 40 so as to permit the escape of air from the chamber through said openings.

I have illustrated and described with particularity the preferred details of construction 45 and arrangement of the several parts; but it is obvious that changes can be made and the essential features of my invention still be employed.

Having described my invention and set 50 forth its merits, what I claim is—

1. In a tubular lantern, the combination of the oil-cup, the ears, as C, attached thereto

and connected together by a cross-plate to form one member of a hinge, the ears, as C', connected together by a cross-plate to form 55 the second member of the hinge and hinged to the other member, and the air-tubes connected to said second member of the hinge, substantially as described.

2. In a tubular lantern, the combination of 60 the oil-cup, the burner-collar, the ears, as C, attached to the oil-cup and connected together by a cross-plate to form one member of a hinge and having openings communicating with the interior of the burner-collar, the ears, as C', 65 connected together by a cross-plate to form the second member of the hinge and hinged to the other member, and the air-tubes connected to said second member of the hinge and having their lower ends located to register with the openings leading into the burner-collar, substantially as described.

3. In a tubular lantern, the combination with the oil-cup and air-tubes, of the collar attached to the upper end of the air-tubes, 75 the globe-holder fitting inside the collar and forming in connection therewith a chamber at the upper portion of the lantern, said chamber having openings for the entrance and exit of air, and a conical collar inside of the globe-holder extending inwardly and upwardly from a point below the opening into the before-mentioned chamber to form an air-chamber to receive air at its upper end and direct it into the outside chamber and thus prevent it 85 from passing down inside the globe-holder to the burner, substantially as and for the purposes described.

4. In a tubular lantern, the combination with the oil-cup and air-tubes, of the globe-holder at the upper portion of the tubes and having openings at its upper end, the cap or cover secured thereto, the conical collar inside of the upper portion of the globe-holder extending inwardly from its lower to its upper end to form an upwardly-tapering interior to the holder at its upper portion, and the deflector-plate above said conical collar, 95 substantially as and for the purposes described.

JAMES H. HILL.
